PANTOGRAPH ENGRAVING MACHINE

Frank Ackerman, Bronx, and Herman Gould,
Brooklyn, N. Y.

Application February 7, 1939, Serial No. 255,020

6 Claims. (Cl. 33—25)

Our present invention relates to a pantograph engraving machine and aims to provide certain improvements therein.

The primary object of our invention is to provide a relatively portable machine of the type specified adapted for reproducing by engraving, characters from type or stencils or facsimile signatures onto flat or slightly curved objects, such as cigarette cases, compacts, vanity cases and the like, formed of metal, plastics, hard rubber, enamel ware and the like. A further object is to provide such machine wherein the pressure of the engraving cutter upon the work is maintained substantially uniform so that the depth of the engraving cut will be substantially uniform regardless of the character, form or any irregularity in the object being engraved. A further object is to provide a pantograph wherein the pivotal connection between certain arms thereof is such as to permit slight relative movement therebetween in a direction perpendicular to the common plane of said arms. A further object is to provide such machine which will be simple in construction and which can be efficiently operated by an unskilled worker after a few minutes instruction.

The foregoing and other objects not specifically enumerated are accomplished by our present invention, the construction and operation of which will be understood from the detailed description which follows when considered in connection with the accompanying drawings, wherein:

Figure 1 is a top plan view of an engraving machine embodying our invention.

Fig. 2 is a side elevation of the machine shown in Fig. 1, when viewed from the right thereof, parts of said machine being broken away to better illustrate certain details of construction.

Fig. 3 is a section taken substantially along the plane of the line 3—3 of Fig. 1.

Fig. 4 is a section taken substantially along the plane of the line 4—4 of Fig. 1.

Referring to the drawings, let 10 indicate a supporting base which is preferably in the form of a hollow truncated rectangular pyramid having at one corner thereof an upright or standard 11 having an offset portion 12 provided with an overhanging lug 13, there being a horizontal shoulder 14 formed between the parts 11 and 12 of the standard. Mounted on the shoulder 14 in clamping relation thereto by a bolt 15 is a split clamping ring 16 which supports an electric motor 17 having a shaft 18 extending in a vertical direction and having a pulley 19 carried thereby.

Extending upwardly through the base 10 and through the overhanging lug 13 is a threaded bolt 20 which constitutes a fixed pivot for a pantograph, the supporting arm 21 of which is held upon the bolt 20 between the lug 13 and a sleeve 22 which in turn is held in position on the bolt 20 by a nut 23. The pantograph supporting arm intermediate its ends has pivoted thereto a second pantograph arm 24 which at its end remote from the pivotal connection extends upwardly and reversely over the arm to provide a U-shaped support 24a for a cutter unit 25. Pivoted connected to the free end of the pantograph supporting arm 21 is a third pantograph arm 26 which is longer than the other arms and at its free end carries a tracing stylus 27. Pivoted connected to the outer end of the second arm 24 and to a point intermediate the ends of the third arm 26 is a fourth pantograph arm 28.

The cutter unit 25 may be of any preferred construction, such for example as described in detail in our co-pending application, Serial No. 248,032, filed December 28, 1938, and consists of an axially rotatable cutter element adapted to be rotated by a driven pulley 29 in a manner to be described.

Coaxially mounted with the pivot pin connecting the arms 21 and 24 is a pair of pulleys 30 and 31, the latter being driven by an elastic belt 32 from the motor pulley 19, and the former being adapted to drive the cutter of the cutter unit 25 through a belt 33. Preferably the shaft 18 of the motor 17 is disposed substantially in the common vertical plane passing through the pivotal axes of the pantograph supporting arm 21 so as to impose but a slight pull on said arm by the driving belt 32 when the central pivot of said arm is moved slightly out of said common plane. When the movement of this central pivot out of said common plane is substantial, there is a tendency for the belt 32 to jerk the pantograph violently out of position and to avoid such action and limit the extent of the pivotal rotation of the pantograph supporting arm about its fixed pivot 20, lugs 34 are mounted on the arm 21 for engagement with the edges of the offset portion 12 of the standard 11.

Mounted below the horizontal sweep of the cutter unit is a work support which consists of a flat plate 35 having a pair of parallel slots 36 adjacent opposite edges thereof and disposed in each of said slots is an upwardly extending screw 37 which supports a clamping bar 38 which is normally biased away from the plate 35 by coil springs 39 mounted upon said screws. The

clamping bar 38 is adapted to be moved down into clamping relation with an article supported on the plate 35 by wing nuts 40. The plate 35 on its underside carries a pair of cylindrical tubular members 41 which telescope within tubular cylindrical members 42, the said cylindrical members being normally biased to move apart by coil springs 43 and are limited in such movement by connecting bolts 44. The telescoping members are held against relative axial rotation through the medium of a key 45 carried by the member 42 and moving in a keyway 46 in the member 41. It is also desirable to prevent the bolts 44 from rotating once they have been adjusted and for this purpose set screws 47 may be mounted in the bases of the members 42 adjacent the hexagonal head of the bolt 44. The telescoping sleeves which support the plate 35 are mounted for movement in cylindrical bosses 20 48 formed in the top of the supporting base 10. Normally the action of gravity causes the work supporting plate to move to a position remote from the cutter and to bring an article which is mounted on said supporting plate into engraving 25 relation to the cutter, it is necessary to move the work support upwardly. To accomplish this we provide an operating shaft 49 which is journaled in bosses 50 formed on opposite sides of the supporting base, said shaft having mounted thereon 30 a finger 51 which is adapted when the shaft 49 is rotated to engage a connecting rod 52 which joins the cylindrical members 42 to move the same upwardly. For rotating said shaft it is provided with an operating arm 53 having at its 35 outer end a handle 54.

Since the articles to be engraved by the machine are not all of uniform thickness it will be apparent that the degree of upward movement of the work supporting plate must be accurately 40 controlled so as to avoid too deep or too shallow an engraving cut in the article. Accordingly, for definitely controlling the degree to which the work supporting plate is elevated we provide an adjustable stop means 55 mounted in a lug 56 extending from one side of the base, said stop 45 means comprising an adjustable screw 57 which is threaded into the lug 56 and a lock nut 58 for holding the screw 57 in adjusted position. It will thus be apparent that the movement of the operating arm 53 downwardly until it contacts the head of the screw 57 will definitely control the 50 upward movement of the finger 44 and hence the upward throw of the work supporting plate.

Because of inequalities in and the usual slight 55 curvature of the surface of the articles to be engraved, it is desirable that the work supporting plate be adapted to "give" or move downwardly when brought under the cutter, the height of which above the base is fixed, and to accomplish this the telescoping sleeves 41 and 42 are such that the sleeves 41 are capable of limited movement against the tension of the springs when subjected to pressure, notwithstanding that the sleeves 42 are held against downward movement.

In the use of the pantograph the application of strains to the operating arm 26 especially in a vertical direction imposes a certain amount of strain on the pivotal connections which if not 70 taken up will soon either cause a bending of the pivots or of the operating arm 26. To prevent such injury taking place we form the pivotal connections so as to permit limited movement between the connected arms in a direction axially of the pivot pins. The specific construction of

these pivot connections as provided at the pivots 59 and 60 are of a form as shown in detail in Fig. 4, wherein the pivotal connection between the arms 26 and 28 is provided by telescoping coaxial bushings on spacing washers 61 and 62, and coaxially with which extends a headed pin 63 having a spring 64 mounted thereon between the head of the pin and the arm 26, said pin being held in position by a cotter pin 65. Preferably the spring enclosed portion of the pin is housed within a dome washer 66 mounted on the pin. A substantially equivalent resilient pivotal connection is provided between the arm 24 and the arm 28 wherein a spring 67 is mounted at the lower end of the pivot pin between the under- 15 face of the arm 28 and a washer 68.

For supporting a templet or facsimile which is to be reproduced by engraving on an article, there is mounted on the supporting base 10 through a pair of spaced uprights 70 a platen 71 20 having thereon suitable guide ways for receiving the templet or facsimile containing sheet and a pair of slidable clamps 72 each provided with a spring clip 73 adapted to hold said templet or facsimile sheet in place. For holding the slidable 25 clamps in fixed relation thumb screws 74 may be employed. For controlling the operation of the electric motor 17 a snap switch 75 may be mounted at the front of the base.

In the operation of the machine, the article, 30 for example a cigarette case 76, is placed on the supporting plate 35 and clamped thereon through the medium of the clamping bar 38 and wing nuts 40. The limiting means 55 are then adjusted to limit the upward movement of the supporting plate to govern the proper depth for the engraving cut in the article. The templet or the facsimile containing sheet is then positioned and held on the platen. The stylus 27 is then brought over into position at the left hand end of the matter to be copied and one is now ready to proceed with the engraving operation. To accomplish this the motor is started by throwing the switch 75, the work supporting base with the cigarette case thereon is elevated by pressing the handle 54 downwardly until the arm 53 contacts with the head of the screw 57 and the stylus is then moved over the matter to be copied. Where a blank is encountered or where it is desired to dot an "i" or cross a "t" it will be apparent that pressure on the handle will be released so as to permit the work to move out of engagement with the cutter until the stylus has been again moved into proper copying position. When the engraving operation is completed the handle 54 is released whereupon the springs 43 again move the work support downwardly, the clamping bar is then released, the engraved article is removed, brushed and finished in the conventional manner.

While we have shown and described a preferred embodiment of our invention it is to be understood that we do not wish to be limited to the specific details of construction disclosed, since these may be varied within the range of engineering skill without departing from the spirit of the invention.

What we claim is:

1. In a pantograph engraving machine or the like, a gravity actuated work support for holding the article to be engraved by the cutter, guide means within which said work support is movable, manually operable means for moving the work support upwardly toward the cutter against the action of gravity and adjustable means for limiting the movement of the work 75

support toward the cutter, said work support comprising a pair of relatively movable members and resilient means between said members whereby one of them is rendered capable of moving 5 relatively to the other away from the cutter after the work support is moved to its adjustable limiting position toward the cutter.

2. A pantograph engraving machine according to claim 1, wherein the relatively movable members of the work support are a pair of telescoping elements which are acted upon by the resilient means.

3. A pantograph engraving machine according to claim 1, wherein the relatively movable members of the work support are a pair of telescoping elements which are acted upon by the resilient means, and wherein the upper of said elements carries a work supporting plate, the telescoping elements being so related and the tension 15 of the resilient means being such that the manually operable means in acting upon one of the telescoping elements operates through the resilient means to move the other telescoping element and the work supporting plate toward 20 the cutter.

4. In an engraving machine or the like, a pantograph comprising a plurality of pivotally con-

nected arms, the pivotal connection between certain of the arms being formed by overlapping parts of the arms having a pin extending therethrough and said pin having a spring mounted thereon and urging the overlapping parts of said arms toward each other but adapted to give to permit limited movement between the connected arms in a direction axially of the pin.

5. In an engraving machine or the like, a work support comprising a substantially flat plate, a 10 clamping bar carried by and extending across said plate, resilient means normally biasing said clamping bar away from the plate and means for holding said clamping bar in engagement with an article to be engraved.

15 6. In an engraving machine or the like, a work support comprising a substantially flat plate having a pair of slots therein, screws extending through said slots, a clamping bar mounted on said screws and extending across said plate, coil 20 springs mounted on said screws and normally biasing said clamping bar away from the plate and nuts adjustable on said screws for limiting the biasing action of the springs.
